UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,233,894.

Specification of Letters Patent. Patented July 17, 1917.

Application filed September 22, 1916. Serial No. 121,562.

To all whom it may concern:

Be it known that I, ALBEN E. LUNDELL, a citizen of the United States, residing at New York, in the county of Bronx and 5 State of New York, have invented certain new and useful Improvements in Telephone-Exchange Systems, of which the following is a full, clear, concise, and exact description.

10 This invention relates to telephone exchange systems, and more particularly to improvements in automatic or semi-automatic telephone exchanges.

15 It is the object of the present invention to provide a new and improved circuit arrangement for controlling the operation of automatic switching devices, which are adapted to hunt for and seize an idle set of terminals representing a telephone line, 20 such as a trunk leading to a selector switch.

25 More particularly the object of this invention is to provide a circuit arrangement for hunting switches which are adapted to be successively set into readiness for operation, whereby the starting of a switch to hunt for a certain set of terminals, is definitely prevented after another switch has been started to hunt for said set of terminals.

30 According to the present invention, a plurality of finder switches adapted to associate a switch controlling device, such as a sender, with a trunk or link circuit assigned by an operator, is successively set in readiness for service preferably under the control of an allotter. Associated with each link or trunk circuit, is a controlling apparatus such as a sequence switch controlling the circuits of a selector by means of which

35 40 45 50 the trunk circuit may be extended under the control of the sender. As soon as the cord finder, which has been previously allotted for service, associates the sender with this trunk line, the sequence switch of the selector should move to a certain operating position. It may happen, that due to some disturbances in the operating mechanism or circuits, the sequence switch cannot move to this operating position, but will stay in a position controlling the starting of the cord finder allotted for service.

In this case, another cord finder, which has been allotted for service, upon the setting of the above mentioned cord finder, will start

to hunt for the assigned trunk and will 55 thus be uselessly set into motion.

To prevent the occurrence of this, the present invention provides means, preferably in the form of a relay associated with the trunk circuit, which will prevent the 60 starting of another cord finder under the control of the sequence switch associated with the same selector, during the time elapsing between the allotment of another cord finder and the movement of the 65 sequence switch into said operating position. This is done by causing the relay to open the starting circuit of the finders as soon as the next cord finder is allotted. The relay maintains the starting circuit open until 70 the sequence switch is moved into the said operating position, in which position the sequence switch contacts controlling the starting circuit, are open.

The drawings represent a semi-automatic 75 telephone system embodying the present invention, and should be considered by placing Figure 2 to the right of Fig. 1, and Fig. 3 below Fig. 2.

Only so much is disclosed of a semi-automatic telephone system as is necessary for a clear understanding of the invention. A more complete disclosure of the circuits controlling the operation of the selector switches, the cord finders, the sender and 85 the associated apparatus, may be had from Patent 1,115,389 issued on January 18, 1916 to A. E. Lundell.

The automatic selector switches shown in the drawings may be of a structure similar 90 to that shown in Patent 1,123,696; the cord-finder switch shown in Fig. 3, however, will be provided with but a single set of brushes.

The sequence switches and the allotted 95 switch shown in the drawings may be similar to the sequence switch structure disclosed in Patent 1,127,808. The numerals which appear adjacent to the contacts of such switches, diagrammatically represented in various portions of the drawing, indicate the positions of the respective switches, at which these contacts are closed with the exception that the controlling contacts or normal contacts, one of which appears immediately above the motor magnet of each 100 of these switches, are open only at the positions indicated by the numerals adjacent

thereto, and therefore the switches can stop in only these positions.

It will be obvious, however, to those skilled in the art, that instead of the apparatus disclosed in the mentioned patents, other apparatus may be successfully employed without departing from the spirit of the present invention.

A full understanding of the invention may be had from the following description and the appended claims.

The subscriber at substation 100, desiring to obtain a connection with a subscriber at station 200, removes his receiver from the switchhook, causing thus the energization of a line relay 101, which, in turn, actuates a calling line signal 102. An A-operator whose telephone head set is shown at 103, noticing the signal 102, inserts a plug 104 into an answering jack 105 in which the calling subscriber's line terminates. A circuit is now closed from ground, through the winding of a cut-off relay 106, the sleeve contacts of jack 105 and plug 104, a resistance 107, and a supervisory signal 108 to grounded battery. The relay 106 becomes energized, and by disconnecting the line relay 101, causes the release of signal 102. Lamp 108 cannot light up due to the fact that a calling supervisory relay 109, which has been energized over the line circuit, closes a shunt around it. By depressing her listening key 110, the A-operator connects her telephone set 103 into telephonic association with the calling subscriber's station 100 over a cord or link circuit 111.

Having received the called subscriber's number, the A-operator depresses a call circuit button 112, and establishes a connection over a call circuit 113 between her telephone 103 and a B-operator's telephone set, shown at 201. The B-operator receives the number of the called subscriber from the A-operator and instructs the latter to extend the calling line to an idle trunk leading to the B-operator's position. Supposing that trunk 114, 115 is to be used, the A-operator inserts a plug 116 into a jack 117 in which the trunk terminates at her board. A circuit is closed thereupon for a called supervisory lamp 118, and the trunk is guarded in the well-known manner.

Another circuit is closed from grounded battery through the left-hand winding of a relay 202, the primary winding of a repeating coil 203, conductor 114, the tip contacts of jack 117 and plug 116, the normal contact of a ringing key 120, and the secondary winding of a repeating coil 121 to ground. Relay 202 becomes energized.

The B-operator proceeds now to build up the connection to the called subscriber's station. By depressing an assignment key 204, she establishes a circuit from ground through the contacts of this key, a contact 205 and

the power magnet of a sequence switch 206 to grounded battery. Under the control of a normal spring 207, the sequence switch is moved out of position 1 and into position 2.

As soon as sequence switch 206 reaches position 2, a starting circuit is completed for a cord finder (Fig. 3) from ground through a sequence switch contact 208, the armature and back contact of a relay 209, conductor 210, contacts 300 and 301 of a sequence switch 302 and the winding of a relay 303 to grounded battery. Relay 303 closes a circuit from ground through its right-hand armature and front contact, a contact 304 and the power magnet of sequence switch 302 to grounded battery for driving this sequence switch out of position 1 into position 2. A circuit is closed thereupon from ground through the right-hand armature and front contact of relay 303, a sequence switch contact 305, and the winding of a magnet 306 to grounded battery. By attracting its armature, magnet 306 presses a cord-finder brush rod 307, carrying wipers 308, 309 and 310, and commutator brushes 311 and 312 against a roller 313 constantly rotating in the direction indicated by the arrow. Wipers 308 to 310 travel over the contacts of a terminal bank 314 in which conductors individual to trunks such as 211, 212 terminate. As soon as the contacts representing trunk 211, 212, the sequence switch 206 of which is in position 2, are reached, a circuit is completed from grounded battery through the winding of a relay 315, a sequence switch contact 316, wiper 309, terminal 317, conductor 318, and a sequence-switch contact 213 to ground. Relay 315 closes a locking circuit for itself from grounded battery through its winding, a sequence-switch contact 319, the right-hand front contact and armature of relay 315, wiper 310, terminal 320, conductor 321, the winding of relay 209 and a sequence-switch contact 214 to ground. As long as sequence switches 206 and 302 are in position 2, relay 209 cannot become energized due to the existence of a shunt path through sequence-switch contacts 316 and 213 to ground.

At its left-hand armature, relay 315 opens a circuit extending from grounded battery through the winding of relay 303, sequence-switch contacts 301 and 322, and the back contact and armature of relay 315 to ground through which relay 303 was held energized when sequence switch 302 left position 1. During the upward travel of the cord finder, brush 311 was riding over a commutator plate 323, the insulated segments 324 of which are so arranged with respect to the terminal bank 314 that when brush 311 contacts with one of them, the wipers 308 to 310 are exactly centered on a set of terminals. As soon, therefore, as brush 311 reaches an

insulated segment 324, after the energization of relay 315, relay 303 becomes deenergized, its holding circuit, extending from ground through commutator brush 311, the 5 conducting plate 323, conductor 325, and the left-hand armature, front contact and winding of relay 303 to grounded battery, being opened. Upon the deenergization of relay 303, a circuit is closed from ground through 10 the right-hand armature and back contact of this relay, a contact 326 and the power magnet of sequence switch 302 to grounded battery, and under the control of a normal spring 327, this sequence switch is moved out 15 of position 2 into position 3. Contact 316 is now open and relay 209 becomes energized and opens at its back contact, the starting circuit for this cord finder.

The B-operator now depresses a starting 20 key 332 for closing a driving circuit through a sequence-switch spring 333 to drive sequence switch 302 out of position 3 and into position 7.

In position 7 of sequence switch 302, a 25 circuit is closed for actuating a cord-finder allotter 360, which is assumed to be in position 1. This circuit extends from grounded battery, through the power magnet of allotter 360, sequence-switch contact 361 and 30 allotter contact 362 to ground, and under the control of a normal spring 363, the allotter is moved into position 2.

A sequence switch 302' controls the operation of a cord finder (not shown), similar to 25 the one represented in Fig. 3, in the same manner as sequence switch 302. Sequence switch 302' is standing now in position 18 where it has been moved in a manner to be described later in connection with sequence 40 switch 302.

When the allotter reaches position 2, a circuit is closed from ground, through allotter contact 364, a contact 365' and the power magnet of sequence switch 302' to grounded 45 battery. Under the control of a normal spring 327', sequence switch 302' is moved out of position 18 into 1 and set in readiness for service. In view of the fact that at this time, sequence switch 206 is still in position 50 2, a circuit might be established from grounded battery, through the winding of relay 303', contacts of 301' and 300' of sequence switch 302', conductor 210, the back contact and armature of relay 209, and sequence 55 switch contact 208 to ground. If the establishment of such circuit would be possible, relay 303' would close a driving circuit through a contact 304' of sequence switch 302' for moving this switch into position 2, whereupon the associated cord finder would be needlessly started, due to the actuation of its motor or driving magnet corresponding to magnet 306. However, as stated, the starting circuit leads through the 60 back contact of relay 209 and as it was set

forth above, the circuits of this relay are so arranged that as soon as sequence switch 302 moves out of position 2, i. e. upon the setting of wipers 308, 310 onto terminals 334, 317 and 320, and while sequence switch 206 is in 70 position 2, relay 209 is energized. It will be seen, therefore, that the needless starting of another cord finder is positively prevented.

When sequence switch 302 reaches position 7, a fundamental circuit is established 75 from grounded battery through the winding of a relay 230, sequence switch contacts 231 and 232, a conductor 233, terminal 334, wiper 308, the windings of a stepping relay 335, the back contact and armature of the upper 80 counting relay 0 and the sequence switch contact 336 to ground. Relay 230 closes a locking circuit for itself over its left-hand front contact and armature, and a circuit from ground, through its right-hand armature and front contact, a sequence switch contact 234, and the power magnet of sequence switch 206 to grounded battery for driving this sequence switch out of position 2 into position 3. 85

In position 3 of the sequence switch 206, its contacts 214 and 270 are closed causing the short-circuiting of relay 209. The deenergization of relay 209 at this time cannot result in the starting of the allotter cord 90 finder associated with sequence switch 302', because sequence switch 206 opens its contact 208 as soon as it is moved out of position 2. Obviously this allotter cord finder may be used to associate the sender (after the setting of the selector) with other trunks, i. e. 95 selectors.

A circuit is closed from grounded battery through the winding of a magnet 235, sequence switch contacts 236 and 237 and the 105 right-hand front contact and armature of relay 230 to ground. By attracting its armature, magnet 235 presses the brush rod 238, carrying wipers 239, 240 and 241, and brush 242 of a selector switch 243 against a roller 110 244, constantly rotating in the direction indicated by the arrow for causing the upward travel of the brush and wipers.

Let us suppose that the called subscriber's 115 number is 9876 and that the operator has depressed keys 328, 329, 330 and 331. Upon the energization of the stepping relay 335, a circuit is established from ground through the armature and front contact of this relay, a sequence switch contact 337, a conductor 120 338, the contact of key 328, conductor 339, the armature and back contact of the upper counting relay 9 and the winding of the lower counting relay 9 to grounded battery. The lower counting relay 9, upon energization, 125 establishes a locking circuit extending from ground through a sequence switch contact 340, conductor 341, the armature and front contact of the lower counting relay 9, the windings of the upper and lower count- 130

ing relays 9 to grounded battery. Due to a shunt path established through the front contact of the stepping relay 335, the upper counting relay cannot become energized. 5 As soon, however, as brush 242 engages a conducting segment 244 of the commutator plate 245, over which it rides, a shunt path is closed to the winding of relay 230, over a sequence switch contact 246, and the stepping relay 335 becomes deenergized permitting thus the energization of the upper counting relay 9. By attracting its armature, the upper counting relay 9 extends conductor 339 through the armature and back 10 contact of the upper counting relay 8 and the winding of the lower counting relay 8 to grounded battery for energizing the latter. 15 As soon as the stepping relay 335 is again shunted out under the control of brush 242, 20 the upper counting relay 8 becomes also energized and the operation of these counting relays will continue until the wipers of selector 243 reach the terminals of a trunk predetermined by the thousands key 328, 25 whereupon the upper counting relay 0 becomes energized and opens at its armature and back contact the fundamental circuit causing thus the deenergization of relays 335 and 230, and the driving of sequence 30 switch 302 out of position 7 into position 9.

Upon the deenergization of relay 230, a circuit is closed from ground through the right-hand armature and back contact of relay 230, a contact 247, and the power magnet of sequence switch 206 to grounded battery for driving this sequence switch out of position 3 into position 8. As soon as this sequence switch is moved out of position 3, the circuit of magnet 235 is interrupted, and assuming that the first trunk in the designated group is idle, the selector wipers will be arrested in their movement.

Key 239 controls the setting of a selector switch 248 and keys 330, 331 the setting of a connector switch 249. The control of these switches is accomplished in substantially the same manner as described in connection with selector switch 243. After the sending of the hundreds series of impulses, sequence switch 302 moves into position 11 and sequence switch 206 moves into position 10. Again, after the sending of the tens series of impulses, sequence switch 302 moves into position 13. Lastly, after the sending of the units series of impulses, sequence switch 302 moves into position 17 and sequence switch 206 moves into position 16. When sequence switch 302 passes through and out of position 16, relay 315 becomes deenergized due to the opening of its circuit at contact 319.

A circuit is thereupon established from ground through sequence-switch contact 350 and the winding of a down-drive magnet 351 to grounded battery. Magnet 351 presses

brush rod 307 against a roller 352, constantly rotating in the direction indicated by the arrow, and the cord finder will thus be restored to normal position. As soon as brush 312 reaches a plate 353, a circuit is established from ground through brush 312, plate 353, a contact 354 and the power magnet of sequence switch 302 to grounded battery for moving this sequence switch out of position 17 into position 18.

Sequence switch 302 remains in position 18 until the allotter again returns to position 1 and closes a circuit from ground, through its contact 362, a contact 365 and the power magnet of sequence switch 302 to grounded battery, whereupon this switch is moved into position 1.

When the called subscriber at station 200 removes his receiver from the switchhook, a supervisory relay 250 becomes energized and closes a circuit including the right-hand winding of relay 202 and the winding of a called supervisory relay 119 in series. The supervisory relay 119 shunts out lamp 118. Under the control of key 120, relay 202 may be controlled to cause the re-ringing of the called station in case of premature disconnection on the part of the called subscriber. The re-ringing of the called station may be controlled in a manner disclosed in Patent 95

1,183,890 issued May 23, 1916, to A. E. Lundell. When the calling and called subscribers are through conversing and hang up their receivers, supervisory relays 109 and 250 become deenergized, and the latter opens the circuit of supervisory relay 119. Lamps 108 and 118 light up, whereupon the A-operator by removing plug 116 from jack 117 causes the deenergization of relay 202 which closes a circuit from ground through its armature and back contact, a contact 251 and the power magnet of sequence switch 206 to grounded battery for driving this sequence switch out of position 16 into position 18. A circuit is then closed from ground through a sequence switch contact 253 for actuating a magnet 255. Magnet 255 presses brush rod 238 against a roller 256, constantly rotating in the direction indicated by the arrow, for causing the restoration of selector 243. When the brush rod reaches its normal position, a circuit is closed from ground through commutator brush 242, a conducting segment 257, a contact 258 and the power magnet of sequence switch 206 to grounded battery, and the sequence switch is moved out of position 18 into position 1. The release of selector 248 and connector 249 may be accomplished in any well-known manner.

What is claimed is:

1. In combination, a selectively operable switch, a plurality of controlling devices therefor, a plurality of finders, any one of which associate one of said controlling 130

devices with said switch, an allotting arrangement for successively setting said finders in readiness for service, and means for preventing the starting of a finder after 5 one of said finders has been set into operation.

2. In combination, a selectively operable switch, a plurality of senders for controlling the operation of said switch, controlling 10 mechanism associated with said switch, a plurality of finder switches each adapted to associate one of said senders with said switch, an allotting mechanism operable upon the completed operation of one of said 15 finders for setting another finder in readiness for service, means operative in a certain position of said controlling mechanism for closing a starting circuit for all of said finders, and means for preventing the closure of 20 said starting circuit in said position of the controlling mechanism after one of said switches has been started.

3. In combination, a selector switch, a plurality of senders for controlling the operation of the same, a plurality of finder switches, a motor associated with each of the 25 said finders to cause it to interconnect one of said senders and said selector switch, an allotter for setting one at a time said 30 motors in readiness for operation, a sequence switch having a plurality of operating positions associated with said selector, a starting circuit for all motors closed in a certain position of said sequence switch, means operative upon the successful operation of one 35 of said finders for actuating said allotter, and means for opening said starting circuit until said sequence switch has moved out of said certain position.

4. In combination, a selector switch, a plurality of senders, a plurality of finder switches, each adapted to connect one of 40 said senders to said selector switch, a motor for each of said finder switches, a sequence 45 switch having a plurality of operating positions associated with said selector switch, a starting circuit for all said motors closed in a certain position of said sequence switch, a relay for controlling said starting circuit, 50 an allotter for rendering a single motor responsive to said starting circuit, means operative upon the successful operation of one of said finders for actuating said allotter to render another motor responsive to said 55 starting circuit, and means for actuating said relay to open said starting circuit dur-

ing the time elapsing between the operation of said allotter and the movement of said sequence switch out of said certain position.

5. In a telephone exchange system, a plurality of lines, a plurality of trunk lines, means including an automatic selector switch for establishing a connection between a calling and a called line, through one of said trunk lines, a plurality of senders for controlling the operation of said selector switch, a plurality of finder switches, each adapted to associate one of said senders with said last mentioned trunk line, a controlling apparatus associated with said selector switch, means operative upon the setting of one of said finder switches for allotting another finder switch for service, if 60 said controlling apparatus is in a certain position, and means for preventing the start- 65 70 75 ing of said last mentioned finder switch.

6. In a telephone exchange system, a plurality of lines, a plurality of trunk lines, means including an automatic selector switch for establishing a connection between a called and a calling line through a 80 trunk line, a plurality of variably operable senders for controlling the operation of said selector switch, a plurality of finder switches, each adapted to associate one of 85 said senders with said last mentioned trunk line, an allotter for setting the finder switches one at a time in readiness for service, means for operating the allotter finder switch while said selector switch is in a normal 90 position, means operative in response to the starting of said sender for actuating said allotter, and means for preventing the operation of an allotted finder switch during the time elapsing between the allotment 95 of said last mentioned finder switch and the starting of said selector switch.

7. In combination, a line, a plurality of finder switches, means associated with each of said switches to hunt for said line, allotting mechanism for successively setting into readiness for service said finder switches, means operated upon the completed setting of one of said finder switches for actuating said mechanism, and means for preventing 100 105 the next allotted finder from hunting for said line.

In witness whereof, I hereunto subscribe my name this 19th day of September A. D., 1916.

ALBEN E. LUNDELL.
